UNITED STATES PATENT OFFICE

150,175

DESIGN FOR A CIGARETTE RACK

Haywood Thomas, New York, N. Y.

Application August 31, 1946, Serial No. 133,007

Term of patent 3½ years

(Cl. D85—2)

To all whom it may concern:

Be it known that I, Haywood Thomas, a citizen of the United States, residing at New York city, in the county of New York and State of New York, have invented a new, original, and ornamental Design for a Cigarette Rack, of which the following is a specification, reference being had to the accompanying drawing, forming part thereof.

The dominant feature of the design resides in the portion of the cigarette rack shown in full lines.

I claim:

The ornamental design for a cigarette rack, substantially as shown and described.

HAYWOOD THOMAS.
